DESIGN FOR A HIGHWAY MARKER

Harry E. Neal, Columbus, Ohio

Application September 15, 1944, Serial No. 115,313

Term of patent 14 years

(Cl. D72—1)

To all whom it may concern:

Be it known that I, Harry E. Neal, a citizen of the United States and a resident of Columbus, Franklin County, Ohio, have invented a new, original, and ornamental Design for a Highway Marker, of which the following is a specification, reference being had to the accompanying drawing forming a part thereof.

In the drawing:

I claim:

The ornamental design for a highway marker, substantially as shown.

HARRY E. NEAL.
